WELL DRILLING MECHANISM

Cornelius R. Wigness and James W. Kirby,
Harlan, Iowa

Application December 14, 1935, Serial No. 54,468

3 Claims. (Cl. 255—11)

This invention relates to an improvement in well drilling mechanism and specifically to the mechanism for moving and controlling the movements of the cables used in drilling and removing 5 the disintegrated rock or dislodged earth and sand therefrom and is designed particularly for use in locations where clay, loam or sand are encountered, and water is generally to be found above bed rock.

10 The invention has for its object, broadly, to provide mechanism having a lesser number of parts than heretofore used so that movements of the cables will require less power, and that there will be less friction than ordinary. Also 15 the invention includes such a construction for the mechanism that manufacture of the same may be carried on at a lesser expense than usual, and that operation will be convenient and may be under control of a single attendant.

20 With the foregoing objects in view the invention presents a new and useful construction, combination and arrangement of parts as described herein and claimed, and as illustrated in the accompanying drawings, it being understood 25 that changes may be made in form, size, proportion of parts and minor details, said changes being within the scope of the invention as claimed.

In the drawings, Fig. 1 is a plan view of operating mechanism embodying our invention, parts 30 of the drums being in section.

Figs. 2, 3, 4 and 5 relate to details. Fig. 2 is a view in side elevation illustrating the use of a movable crank for operation of the drill. Fig. 3 is a side view of a driven gear wheel and an idler 35 gear wheel in engagement therewith. Fig. 4 is an end view of a clutch and its automatic brake, each clutch and its brake being provided for an end of a drum, and Fig. 5 is a view of a sand-pump partly in section.

40 Referring now to the drawings for a more particular description, the mechanism consists, in part, of a power shaft 5 provided with a pulley 6 adapted to be rotated by any suitable means, said shaft having bearings 7 on a frame 8, and keyed 45 on said shaft to rotate therewith is a small gear wheel 9.

50 Numeral 10 indicates a sand-drum which is loosely mounted on the shaft 5, said sand-drum being provided at one of its ends with a clutch-wheel 11.

55 Numeral 12 indicates an idler shaft having bearings 13 on the frame 8 and provided at its ends with cranks 14 and 14'. At 15 is indicated a second drum which is mounted as an idler on

this shaft, said drum being provided at its end with a second clutch-wheel 16.

At 17 is indicated a gear wheel which is in mesh with the gear wheel 9, and is mounted as an idler on said shaft 12.

The parts above named are all that relate to the present invention except certain brakes, clutches and hand levers which will be described and which relate to operation. It is considered that the mechanism now provided may be used 10 to great advantage in connection with the derricks and parts thereon of ordinary well-drilling machines.

It will be understood that, as shown in Fig. 2 of the drawings, a drill x may be attached to the 15 cable 19' and that the cable may be reciprocated longitudinally to permit the drill to have suitable vertical strokes in a well, the "churning" movements or strokes of the drill operating to dislodge the earth and to break up the rock, said drill 20 operating at varying depths in the ground, and the cable and drill being lowered into the well for this purpose.

Also for purposes of drilling wells the cable 19, as shown in Fig. 2, is generally wound upon a 25 drum 15 and is supported on pulleys 18, 20 and 21, the pulley 20 together with arm 22 having a rocking movement from the pivot 23 on a standard 24 to permit the drill to have a drop movement, a coupling-bar 25 being used for connecting the pivot of the pulley 20 to the crank 14, the length of the stroke of the drill, obviously, being equal to twice the length of the crank.

It will be understood that the parts shown in Fig. 2 are used in duplicate for reciprocating the 35 drill-cable 19' vertically, said duplicate part not being shown. In Fig. 2 only crank 14 is shown, but for drilling, both of the cranks 14 and 14' are used, and an extra operating-cable 19' is used and is joined to the cable 19 as indicated at 40 x' these two operating-cables being secured to the cranks 14 and 14' and attached to the drill-cable 19.

The drum is provided with a cable 26, and upon this cable is secured a sand-pump 2, and for lowering the sand-pump into a well the idler drum 10 is permitted to rotate in one direction under control of a brake 31 for the clutch-wheel 11, said brake being pressed lightly against said clutch-wheel by movement of the clutch-member 50 36 which is slidably mounted on the shaft 5 and is under control of a hand lever 35. To elevate the sand-pump from the well the brake is pressed firmly on the wheel-clutch 11 during the rotation of the power shaft 5.

In order that the objects of the invention may be attained as first mentioned, certain control means, including brakes, clutches and hand-levers are employed, the result being that a lesser number of parts will be required for operation.

For instance, when it is required to elevate the drill from a well, a hand-lever 27 is used for moving the clutch-member 28 into engagement with the idler gear wheel 17 to cause rotation of the shaft 12. A second hand-lever 29 is then used for moving a second clutch-member 30 into engagement with the second clutch-wheel 16, the result being that the rope or cable 19 will become wound on the drum 15 for elevating the drill.

To permit the drill to move to the bottom of a well, the second drum 15 is permitted, as an idler on the shaft 12, to have a rotation in a reverse direction to that last mentioned, under control of a brake-member 31.

Two of these brakes 31 are used, one being provided for the first clutch-wheel 11 and the other for the second clutch-wheel 16. Since the clutch-wheel 11 is illustrated in section the brake therefor is not shown, but will be understood by reference to Figs. 1 and 4 of the drawings.

This brake is automatic in operation and is important since wells may have a considerable depth, and since the drill as well as the sand-pump 2 have a considerable weight, the speed or movement thereof, when one of them is lowered in a well, should be under control to avoid possible breakage.

As best shown in Fig. 4, the break 31 is provided with a clamping-arm 32, and by use of a bell-crank 33 which is pivotally connected with said arm 32 and is also connected with a second hand-lever 29 by means of a link 34, a movement of said hand-lever for releasing the clutch-member 30 from the clutch-wheel 16 will cause the brake 31 to be pressed against the periphery of the clutch-wheel 16.

In the operation of drilling, the drum 15 is not rotated, the clutch-member 30 by use of the hand-lever 29 being disengaged from the clutch-wheel 16, but by use of the hand-lever 27 the clutch-member 28 is moved into engagement with the idler gear-wheel 17 which causes rotation of the shaft 12 and actuation of the cranks 14 and 14', and since the cables 19' will be mounted as above mentioned, the drill will be operated.

Whenever it is required to remove sand and loose earth or pieces of rock from the well, the hollow receptacle 2 (Fig. 5) generally called a "sand-pump" is used as above described.

The clutch 36, for its immediate movements, is provided with a rock-bar 37, one of its ends being pivotally fulcrumed at *a*, said rock-bar being attached to an arm of a bell-crank 38, and the other arm of this bell-crank being connected with the hand-lever 35, and a longitudinal movement of this last named lever will move the bell-crank 38 for moving the rock-bar 37 and clutch-member 36.

The rock-bar 37 is fulcrumed at one end as indicated at *b*, and the hand-lever 29 is fulcrumed at its end as indicated at *c* on the frame. The letter *d* indicates the fulcrum for the end of hand-lever 27.

The use of the well-drilling and sand-lifting mechanism described herein will be appreciated on account of its advantages. It will be noted

that only three hand-levers are required for operation and that they are disposed at one side of the mechanism and are near each other so that all operation may be under control of a single attendant.

Also since only two shafts are now used, the entire mechanism will occupy a limited area, and this is of great advantage.

Well drilling machines and their sand-pumping means generally used are mounted on large specifically constructed vehicles. By use of the present invention a lesser wheel-base will be required as a carrier, the result being the saving of a considerable expense.

We claim as our invention:—

1. In well-drilling and sand-pumping mechanism, an idler crank-shaft, an idler gear wheel on the idler crank-shaft provided with a clutch, an idler drum on the idler crank-shaft provided with a clutch-wheel, a drill-supporting cable on said drum, a power-shaft, a gear wheel carried by the power-shaft in mesh with the idler gear wheel, a second drum, said second drum being mounted as an idler on the power-shaft and provided with a clutch-wheel, a sand-pump supporting-cable on the second drum, a clutch-member on the crank-shaft for the clutch-wheel of the first named drum, and a clutch-member on the power-shaft for the clutch-wheel of the second drum.

2. In well-drilling and sand-pumping mechanism, an idler crank-shaft, an idler drum on the crank-shaft, a drill-supporting cable on said drum, a power-shaft, a second idler drum on the power shaft, a sand-pump supporting-cable on the second drum, co-operating devices on the power-shaft and crank-shaft for causing rotation of the crank-shaft by action of the power-shaft, co-operating devices on the first named drum and crank-shaft to cause rotation of said first named drum by action of said crank-shaft, co-operating devices on the power-shaft and second drum to cause rotation of the second drum by action of said power-shaft, a rock-arm mounted to swing in a circle's arc for longitudinal reciprocation of the drill-supporting-cable, a link pivotally mounted on the crank of the crank-shaft and pivoted to the link, and guide-pulleys engaged by said drill-supporting-cable for controlling the direction of movements of said cable.

3. In well-drilling and sand-pumping mechanism, an idler crank-shaft provided at its ends with crank-arms, an idler drum on the idler crank-shaft, drill-supporting cables on said drum, a power-shaft, a second idler drum on the power-shaft, a sand-pump supporting-cable on the drum of the power-shaft, engaging co-operating devices operative at will to cause rotation of the idler crank-shaft by action of the power-shaft, engaging co-operating devices operative at will to cause rotation of the first named drum by action of the crank-shaft, engaging co-operating devices for causing rotation of the second drum by action of the power-shaft, a pair of rock-arms mounted to swing in a circle's arc for longitudinal reciprocation of the drill-supporting cables, a pair of links each pivotally mounted on a crank-arm and pivoted to a crank-arm, and guide-pulleys for controlling the direction of movements of the drill-supporting cables.
